CLAIM

The ornamental design for pants as shown and described.

DESCRIPTION

FIG. 1 is a front view of pants;
FIG. 2 is a back view thereof;
FIG. 3 is a top view thereof;
FIG. 4 is a bottom view thereof;
FIG. 5 is a right view thereof;
FIG. 6 is a left view thereof;
FIG. 7 is a front perspective view thereof;
FIG. 8 is a rear perspective view thereof;
FIG. 9 is an additional front view thereof;
FIG. 10 is an additional rear view thereof;
FIG. 11 is an additional front view in an alternate environment; and,
FIG. 12 is an additional rear view in an alternate environment.

The diagonal lines shown in the drawing Nos. 9 and 10 form no part of the claimed design. In drawing Nos. 9 and 10, the patches marked with hatching lines are pants sections where the tension is strong.

The broken lines in the drawings illustrate portions of the pants and form no part of the claimed design.

1 Claim, 12 Drawing Sheets
